SKI POLE

Thomas W. Bryant, Torrington, Conn., assignor to Union Hardware Company, Torrington, Conn., a corporation of Connecticut

Application June 6, 1939, Serial No. 277,591

5 Claims. (Cl. 280—11.37)

My invention relates to what are known as ski poles.

One object is to provide a light but strong pole.

Another object is to provide a pole with a snow shoe, wheel or ring which can be readily attached or assembled.

Another object is to provide a convenient means for securing the snow shoe to the pole without weakening the pole.

10 Another object is to provide a ski pole which is neat and attractive in appearance.

Another object is to provide a construction in which the snow shoe can be readily detached from the shaft for repair or shipment.

15 Preferably the pole has a tubular shaft of tempered steel or other suitable alloy. The snow shoe consists of an outer ring with cross straps supported on the shaft by a sort of sling formed of two narrow straps interwoven with the cross straps and having their ends secured to a pin or pins which pass through a hub member tightly affixed to the shaft.

Fig. 1 is a perspective small scale view of a ski pole embodying one form of my invention.

20 Fig. 2 is a lower end view on a larger scale showing the snow shoe.

Fig. 3 is a fragmentary section and side view showing the method of securing the shoe to the shaft.

30 Fig. 4 is a side view of a fragment of shaft with the hub in section.

Fig. 5 is a transverse sectional view of the shaft and hub.

Fig. 6 is a transverse sectional view of the 35 shaft on the plane of the line 6—6 of Fig. 1.

Fig. 7 is a detail view of one of the supporting sling straps.

The shaft 10 may be formed of a suitable steel or alloy tube light in weight and yet sufficiently strong for the purpose. This may be plated, enameled or otherwise coated outside and inside if desired in order to avoid corrosion and in order to ornament it if desired. Any suitable handle or grip portion 11 will be provided at the upper end and a suitable tip 12 at the lower end, the latter being preferably of metal inserted and held in the small end of the tubular shaft.

The central portion of the shaft is preferably grooved at 13 to form in effect three ribs to re-

50 inforce and stiffen the shaft between the handle and the shoe.

The shoe has a frame preferably in the form of a ring 14 of suitable material (such as duralumin) to which is attached a number of flexible straps 15 of leather or other suitable material.

Each strap has a central opening 16 preferably in the form of a mere slit to receive the shaft 10 and the straps are arranged like the spokes of a wheel. These straps may merely overlap each other or be interwoven if desired. The outer ends 17 of the straps are wrapped around the ring and secured for instance by rivets 18.

A hub 19, for instance, of duralumin is secured to the shaft for instance by a drive fit and by brazing or otherwise attaching it without cutting, drilling or otherwise weakening the shaft. This hub has passages 20, 20 to receive a cotter pin or pins 21 preferably on opposite sides of the shaft. This pin 21 supports a sling formed of two straps 22 which pass through and around 15 the main straps 15, 15 on opposite sides of the shaft and have their ends 23 perforated to receive the pin. Washers 24 are preferably provided to assist in holding the straps 22, 22 in place and the end 25 of the cotter pin will be bent over as 20 shown. Preferably the two straps 22, 22 pass through separate straps 15, 15 so as to tie them together.

This arrangement gives adequate flexible support for the snow shoe without weakening the shaft. It also permits of ease of assembly and separation without the necessity of special tools.

Although I have shown and described the preferred form of my invention, it will be understood that the claims are intended to be construed to cover the invention as broadly as the prior art will permit.

I claim:

1. A ski pole consisting of a metallic tubular shaft, a hub member fitted on said shaft adjacent one end thereof, a cotter pin extending through said hub member at one side of the shaft, a pair of flexible straps fastened at their ends to the opposite ends of said pin said straps embracing opposite sides of said shaft, a plurality of radially disposed flexible straps supported by said pair of straps in interwoven relationship at their center portions and a ring supported on the outer ends of said radial straps, the edges of all of said straps at their central portions being adapted to contact the shaft and form a flexible bearing for the shaft to permit limited universal tilting of the ring relative to the shaft.

2. A ski pole consisting of a metallic tubular 50 shaft, a hub member fitted on the shaft adjacent one end thereof and provided with tangentially disposed openings on opposite sides thereof, a bifurcated pin with its bifurcations extending through and beyond the ends of said open- 55

- ings, a pair of flexible straps fastened at their ends to the opposite ends of said pin and spaced to permit said shaft to pass therebetween, a plurality of radially disposed flexible straps supported by said pair of straps and positioned in overlapping relationship at their central portions and interwoven with said pair of straps, the overlapping portions of said straps being slitted for receiving the shaft therethrough, and a ring supported on the outer ends of said radial straps, the walls of said slits in said radial straps and the edge walls of said pair of straps forming a flexible bearing for the shaft to permit limited universal tilting of the shaft relative to the ring.
- 15 3. A ski pole consisting of a metallic tubular shaft member, a hub fitted on the shaft adjacent one end thereof, the central portion of said hub being formed with an annular enlargement provided with tangentially disposed openings on opposite sides thereof, a cotter pin with its bifurcated portions extending through and beyond the ends of said openings, a flexible sling supported by the ends of said pin, and a snow shoe supported by said sling for movement along the shaft and for universal tilting movement, said shaft being formed with longitudinally extending arcuate ribs, said ribs having a cross section radius such as to provide three ribs in a shaft having a maximum diameter of approximately $\frac{5}{8}$ of an inch.
- 20 4. A ski pole consisting of a metallic tubular shaft, a hub member fitted on said shaft adjacent one end thereof and formed with a tangent-

tially disposed opening at each side, fastening means having separate shank members extending through said openings, a pair of flexible straps secured at their ends to the opposite ends of said shank members, said straps embracing 5 opposite sides of said shaft, a plurality of radially disposed flexible straps supported by said pair of straps in interwoven relationship at their center portions and a ring supported on the outer ends of said radial straps, the edges of all of 10 said straps at their central portions being adapted to contact the shaft and form a flexible bearing for the shaft to permit limited universal tilting of the ring relative to the shaft.

25 5. A ski pole consisting of a metallic tubular 15 shaft, a hub member fitted on said shaft adjacent one end thereof and formed with a tangentially disposed opening at each side, a plurality of radially disposed flexible straps overlapping at their central portions and formed with slits at 20 said portions for receiving the tubular shaft therethrough, a ring supported on the outer ends of said radial straps, flexible means for suspending said radial straps and ring from said hub including a pair of straps interwoven through the 25 slits of the overlapping portions of said radial straps and metallic means for fastening the ends of said pair of straps to said hub having portions extending through said tangential openings in the hub and a device on the opposite ends of said 30 extending portions for securing the ends of the pair of straps thereon.

THOMAS W. BRYANT.
